COOLING X-RAY TUBES

Edward B. Graves, South Euclid, Ohio, assignor to Picker X-Ray Corporation Waite Manufacturing Division, Inc., Cleveland, Ohio, a corporation of Ohio

Application February 23, 1940, Serial No. 320,323

6 Claims. (Cl. 250—89)

This invention relates to cooling of X-ray tubes.

One object of the invention is to provide improved means for cooling an X-ray tube adapted to dissipate the generated heat with sufficient rapidity so that neither the tube nor its mounting parts or connections reach undesirable high temperatures, and enabling the tube to be used at full capacity for extended periods of time without either harmful effects to any of the apparatus or discomfort to operator or patient.

A further object of the invention is to provide improved cooling means for X-ray tubes in which suitable provision is made for dissipating the heat by convection in one or more fluids and by conduction from fluid to fluid, where more than one fluid is used, or by radiation to the atmosphere, as the case may be.

A further object is to provide an improved X-ray tube mount of generally standard form with the tube enclosed in a shell within which an insulating and more or less heat conducting fluid is circulated, said shell being surrounded by an enclosing casing forming two closely contiguous walls, and hence an annular chamber, through which air or other suitable fluid may be caused to flow for cooling purposes.

Further objects of the invention are in part obvious and in part will appear more in detail hereinafter.

In the drawing, which represents one suitable embodiment of the invention, Fig. 1 is a central longitudinal section; Fig. 2 is an end view from the right in Fig. 1; Fig. 3 is a sectional elevation on approximately the line 3—3, Fig. 1; and Fig. 4 is a similar section on approximately the line 4—4, Fig. 1, looking in the direction of the arrows.

The X-ray tube itself requires no extended description because it is of usual form, including the hollow glass body 1 in which is mounted the anode 2, usually a heavy piece of copper either hollow or solid, carrying the inlaid target 3, the outer end of said anode extending out through one of the ends of the hollow glass body. The anode of course is an excellent conductor of the heat produced, which is dissipated largely from that end of the anode which extends beyond the glass body.

The tube body is suitably mounted in an enclosing shell, marked generally 5, usually made of aluminum, an aluminum alloy, or other suitable light material, provided on one side, opposite the target 3, with the usual window 6, and on its opposite side with hollow tubular extensions 7

having cavities 8 in which are inserted terminals (not shown) connected to the lead wires for the tube circuits.

One end of the shell supports the usual expansion device, such as the Sylphon bellows 9, arranged to compensate for variations in volume of the fluid within the shell as the result of changes in temperature for one reason or another. Frequently such expansion chambers have been mounted one in each end of the tubular shell, but according to the present invention but a single expansion device is employed, the other end of the shell serving to support fluid circulating means, as will more fully appear hereafter.

The tube, of course, is rigidly but removably mounted within the shell, so that the target is in its central longitudinal axis and opposite the center of the window 6. For this purpose the opposite ends of the tube are mounted in supports 10, 11 attached to the stationary shell or to a part fixed thereto, such as to the sleeves 12 into which the wire carrying terminals are inserted. Any other suitable tube supporting means may be employed.

The shell chamber 13 is filled with a suitable insulating liquid which also is a more or less efficient heat carrier, such as a suitable oil, and to more rapidly dissipate the heat means is provided for causing circulation or flow of said oil within chamber 13. The means shown comprises any suitable oil moving device, such as the impeller 14 mounted on the shaft 15 of an operating device, such as an electric motor 16, rigidly mounted within a closing cap 17 on one end of the tubular shell 5. The motor and impeller preferably are mounted coaxially with the shell axis, and means is provided whereby said impeller, when operating, keeps the entire body of the oil constantly in motion, circulating all of it, at one time or another, into close or intimate heat conducting relation with the shell wall 5, so that the heat carried by the oil may be absorbed by and then radiated from said wall and thus become dissipated.

The means shown for this purpose is a tubular shield or guide 18, which may be made of lead, Bakelite or other suitable material, but is here assumed to be made of lead (with an opening for window 6) so as to serve not only to assist in directing the flow of the heat dissipating liquid, but also as a shield for the X-rays generated. Tube 18 is immovably mounted in the shell in any suitable manner. As shown in Fig. 5 its upper curved surface is held tightly against

pads 18a on shell 5 by the window assembly, its outer surface being near to but spaced from the shell wall and said tube terminating at its ends short of the ends of the chamber 13.

Assuming the shell chamber to be filled with oil with motor 16 in operation, the impeller produces a suction effect along the shell axis, causing the oil along the center of chamber 13 to flow to the right in Fig. 1 or toward the impeller, and then to flow radially outwardly and back along the inner surface of the shell wall to the left in Fig. 1 through the annular space between shield 18 and the shell, finally re-entering the other end of shield 18 and again flowing to the right along the outer surface of the X-ray tube 1 and its anode 2.

As a consequence of the described liquid flow, the liquid absorbs the heat generated by and within the tube 1, and that conducted by the anode 2, and carries and gives it up to the metal of the shell, from the outer surface of which it may be dissipated in any suitable manner, fins, ribs, knobs or other devices (not shown) for increasing the area of exposed heat radiating surface of said shell of course improving efficiency.

Under some circumstances improved cooling effects are secured by the provision of means for dissipating the heat from the shell wall by the use of another fluid.

In the arrangement shown the shell wall is surrounded by a thin metal jacket 20, made from steel or other suitable material shaped in generally tubular form, with openings where necessary, such as at the window 6. This jacket is closely spaced from the outer surface of the shell, but is rigid with relation thereto. For example, the jacket ends may be provided with short spacing legs 21 separated by openings for air circulation.

As shown in Figs. 1 and 3, any suitable means is provided for forcibly moving air through the annular space 22 between shell 5 and jacket 20, such as the fan or blower marked generally 23, enclosed within a casing 24 mounted upon the jacket, and in which casing is also enclosed a suitable electric driving motor 24a for the blower, the latter being adapted when operated to receive atmospheric air through the inlet 25 and impel it through the blower outlet 25a into and along the annular cavity 22 toward both open ends of the shell, through which it is discharged to atmosphere.

In operation, therefore, assuming the shell 5 to be filled with oil and the X-ray tube to be in operation, both motors 16 and 24a are started. During operation all of the heat generated in or by the X-ray tube is absorbed by the circulating oil, which carries it by convection to the wall of the shell 5, from which it is either dissipated directly by radiation or is transmitted to the air current flowing along its outer surface, which by convection carries the heat away to the outside air.

For simplicity of illustration the circuit wires for the two motors are omitted, but it will be understood that they are connected to a receptacle 30 to which the usual attachment plug (not shown) may be connected.

In X-ray tubes of this character as heretofore mounted and operated without cooling means, but with oil within the shell, it has been found that within ten minutes of normal operation the temperature rises to above 500° F., whereas with the present cooling system in operation the temperature does not exceed 200° F. or less and may be maintained at that value throughout operation

of the tube over an indefinite period. As a consequence neither the tube nor its mounting parts are subjected to an undesirable temperature and tube operation may be carried on at full capacity for extended periods of time without either injury to the apparatus or discomfort to operator or patient. Other advantages of the invention will be apparent to those skilled in the art.

What I claim is:

1. In combination, a hollow shell provided with a chamber, an X-ray tube mounted in said chamber and spaced from the wall thereof, said shell providing one large liquid-tight chamber adjacent said tube and without external passages, said chamber being filled with a heat conducting electric insulating liquid, an impeller within said chamber for causing motion of said liquid to conduct the heat produced by said tube to the shell wall for dissipation thereby, means mounted on said shell for operating said impeller, a hollow casing enclosing said shell and spaced therefrom to form an annular cavity through which air may flow for absorbing heat from the shell wall and dissipating it by convection, and means mounted on said shell for causing air flow through said cavity.

2. In combination, an elongated hollow shell provided with a chamber, an X-ray tube mounted in said chamber and spaced from the wall thereof to provide an annular elongated space between the walls of the shell and tube, said space being filled with a heat conducting electric insulating liquid, a tubular guide in said annular space, an impeller mounted in one end of said shell for causing circulation of said liquid through said elongated space in one direction within and in the other direction outside of said guide, a hollow casing enclosing said shell and spaced therefrom to form an annular cavity through which air may flow for absorbing heat from the shell wall and dissipating it by convection, and means for causing air flow through said cavity.

3. In combination, an elongated hollow shell provided with a chamber, an X-ray tube mounted in said chamber and spaced from the wall thereof to provide an annular elongated space between the walls of the shell and tube, said space being filled with a heat conducting electric insulating liquid, a tubular guide in said annular space, an impeller mounted in one end of said shell for causing circulation of said liquid through said elongated space in one direction within and in the other direction outside of said guide, a hollow casing enclosing said shell and spaced therefrom to form an annular cavity through which air may flow for absorbing heat from the shell wall and dissipating it by convection, and air moving means mounted upon said casing with its outlet communicating with said annular cavity for directing a current of air therethrough.

4. In combination, a hollow heat-conducting shell providing a liquid-tight chamber, an X-ray tube mounted in said chamber and spaced from the wall thereof, said shell providing one large chamber adjacent said tube and without external passages, said chamber being filled with a heat conducting electric insulating liquid, an impeller within said shell and immediately adjacent said tube for causing motion of said liquid to conduct the heat produced by said tube to the shell wall for dissipation thereby, means for operating said impeller, and means for causing a flow of cooling fluid against the external surface of said shell.

5. In combination, a hollow heat-conducting shell providing a liquid-tight chamber, an X-ray tube mounted in said chamber and spaced from the wall thereof, said shell providing a large chamber adjacent said tube, said chamber being filled with a heat conducting electric insulating liquid, means within said shell for causing motion of said liquid to conduct the heat produced by said tube to the shell wall for dissipation thereby, and means for causing a flow of cooling fluid 10 against the external surface of said shell.

6. X-ray tube cooling means consisting of a

hollow heat-conducting shell providing a liquid-tight chamber, an X-ray tube mounted in said chamber and spaced from the wall thereof, said shell providing one large chamber adjacent said tube and without external passages, said chamber being filled with a heat conducting electric insulating liquid, an impeller within said shell and immediately adjacent said tube for causing motion of said liquid to conduct the heat produced by said tube to the shell wall for dissipation thereby, and means for operating said impeller.

EDWARD B. GRAVES.
